OSCILLATING GRINDER.

1,299,711.

Specification of Letters Patent. Patented Apr. 8, 1919.

Application filed November 7, 1916. Serial No. 130,082.

To all whom it may concern:

Be it known that I, FREDERICK HENRY HALSTEAD, a citizen of the United States, and a resident of Worcester, county of Worcester, and State of Massachusetts, have invented an Improvement in Oscillating Grinders, of which the following description, in connection with the accompanying drawings, is a specification, like characters on the drawings representing like parts.

This invention pertains to improvements in grinders and more particularly, though not exclusively, to improvements in oscillating grinders for grinding races for ball bearings and the like. This class of work is best done by relative arcuate oscillation of the rotating work and the rotating grinding tool. It has been found in practice that a higher grade of work can be done by arcuately oscillating the work than by oscillating the tool. This is probably for the reason that the rate of rotation of the work about its axis is much lower than the rate of rotation of the grinding tool and consequently less "chatter" is present when the work is oscillated than when the tool is oscillated. For the purpose of many phases of the present invention, either work or tool may be arcuately oscillated. In this application the word "oscillation" and the like is used in its true sense of arcuate oscillation or rocking.

It has heretofore been the usual practice to oscillate the oscillating element of tools of this class by or through the medium of a crank, connecting rod and oscillating arm, or by cam or similar mechanism, in which the rate of oscillation of the oscillating member is variable, usually being more rapid at or near the center of oscillation than toward the ends thereof. There is always sufficient spring in machines of this class to render the amount of material abraded in some measure dependent on the relative period of contact of the work and grinding tool. Thus the previous grinders referred to have produced races which are not truly arcuate in cross section, but which are somewhat flattened toward the edges of the race.

Another disadvantage of oscillating grinders, in which the tool and work are relatively arcuately traversed at variable speed, is the loss of efficiency arising from a lowered average speed of relative traverse,

for the proper maximum speed must not be exceeded at the fastest portion of the traverse and the rest of the traverse being slower, necessarily reduces the average rate of traverse and the efficiency of the machine.

Another defect of ball race grinders as previously constructed, arises from the unavoidable spring of the machine, in that if the oscillation be stopped while the tool is in contact with the work, the tool will continue to grind for a considerable period of time, without any traverse feed of either tool or work, thus abrading an irregularity in the contour of the race. One feature of the present invention is to insure stoppage of such oscillation at the end of an oscillation when the work and grinding tool are not in contact. This has the additional advantage that the work and tool are in position to be relatively moved apart for inspection of the work without disturbing the adjustments, should it be necessary to continue the grinding operation.

A third object of my invention is to provide a transverse feed, which is automatically discontinued when the work and tool are separated for inspection of the work, or for any other reason.

A fourth object of my invention is to provide a transverse feed of improved design, which operates when the work and tool are in proper axial relation to one another, but only when the work and tool are not in contact with each other.

My invention also provides improved means for changing the amplitude of relative oscillation of tool and work, and improved means for changing the field of oscillation of the oscillatory element. In connection with changes of amplitude of oscillation of the work, my invention maintains a constant relative speed of oscillation of tool and work, whether the amplitude of oscillation be increased or decreased. As heretofore constructed machines of this class have been provided with step or cone pulleys or the like, which provided a rough adjustment for securing the desired relative traverse of tool and work. As will hereafter appear, no such adjustment is necessary in connection with my invention and an absolutely constant relative traverse is provided, regardless of changes in the amplitude or field of oscillation.

The above improvements while peculiarly advantageous in combination with each other, may be used to advantage separately on any type of oscillating race grinder.

5. Other objects and advantages of the invention will appear in the description.

The drawings show an illustrative embodiment of a preferred construction of my invention, of which—

10. Figure 1 is a side elevation partly in section;

Fig. 2 is a vertical section taken on the center line of Fig. 1;

15. Fig. 3 is a partial end elevation of the preferred construction illustrated in Fig. 1;

Fig. 4 is a partial vertical transverse section on the line 4—4 of Fig. 1;

Fig. 5 is a side elevation partly in section on the line 5—5 of Fig. 4;

20. Fig. 6 is a plan view of a portion of the transverse feed mechanism shown in Fig. 1;

Fig. 7 is a vertical section partly in elevation on the line 7—7 of Fig. 6; and

25. Fig. 8 is a plan view partly in section on the line 8—8 of Fig. 2.

In the illustrative embodiment of my invention shown in the drawings, I have shown a chuck 9 holding the work 10 and mounted on the work spindle 11, which is 30 rotated in bearings 12 by a belt (not shown) on the pulley 13. The specific chuck 9 and work 10 illustrated are adapted for interior race grinding, but a chuck for exterior race grinding may be substituted in the well 35 known manner.

The work spindle bearings 12 and parts carried thereby are preferably longitudinally adjustable on the longitudinal work slide 14, by means of a hand screw 15, while 40 said bearings 12 and parts carried thereby, are preferably transversely adjustable on the transverse work slide 16 by the hand screw 17.

As before stated, I prefer that the work 45 10 be oscillated relative to the grinding tool 18, rather than that the tool 18 be oscillated relative to the work, and to this end I have provided an oscillatory work support typified by the oscillatory element 19 on which 50 the work holding chuck 9 is carried, preferably with the interposed transverse adjustment slides 14 and 16, as before described. The oscillating element may be and preferably is mounted on a pivotal 55 shaft 20, which is preferably oscillated by constant-speed-oscillating means typified by the following preferred construction. On the shaft 20 I preferably provide a worm gear 21, adapted to be alternately engaged 60 on its opposite sides by worms 22 and 23 (Fig. 8), mounted in the swinging frame 24, which is pivoted at 25 to the frame of the machine. The worms 22 and 23 may be 65 driven by a pulley 26 (Fig. 8), which may drive the worm 22 directly and which may

drive the worm 23 through gears 27—28—29. As the worms 22 and 23 rotate continuously in the same direction, but on opposite sides of the worm gear 21, the gear 21 will be oscillated in opposing directions, as and 70 when the frame 24 is swung from one side to the other to alternately engage the worms 22 and 23 with the worm gear 21. It is highly desirable that the constant-speed-oscillating means include reversing means, the operation 75 of which is controlled by the movement of the oscillatory means, that the amplitude of oscillation of the oscillatory means be variable and that the field of oscillation of the oscillatory means be variable. To this end, in the illustrative embodiment of my invention shown in the drawings, I have shown the swinging frame 24 (Figs. 2 and 3) provided with a projecting portion 30 and the oscillating support provided with 80 tappets 31—32, which are preferably adjustably attached thereto. A preferred construction for transmitting movement from the tappets 31—32 to the swinging frame 24, includes the projection 33 in the path of 85 the tappets 31—32 and reciprocable with a slide 34 having a bearing 35 on the main frame 36. Attached to, and reciprocable with the slide 34, is a double wedge or cam 37 adapted to alternately depress lugs 38— 90 39 in levers 40—41, which levers are fulcrumed at 42 and each of which is provided at one end with a catch 43—44, adapted to be alternately engaged with and disengaged from the projection 30 of the swinging cage 100 24, as the levers are rocked by the cam 37. The force which rocks the swinging cage 24 is alternately supplied by the ends 44—45 of the levers 40—41, through spring supported projections 46 and 47, respectively. 105

In the position shown in Fig. 3, the oscillating support 19 is traveling from right to left. When the tappet 32 strikes the projection 33, the latter will shift the cam 37, depressing the lug 38 and rocking the lever 110 40. The end 44 of the lever 40 will compress the spring supported element 46 to a considerable extent before the catch 43 is disengaged from the swinging frame projection 30. When the catch 43 is disengaged, the spring supported projection 46, acting against the lever end 44 will shift the swinging frame 24 (Fig. 8), thereby disengaging one of the worms 22—23 from the worm gear 21 and engaging the other 115 120 125 shaft 20. During this traverse of the swinging frame, the projection 47 will rock the lever 41, thereby causing the catch 44 to engage the swinging frame and hold it in shifted position until the reverse movement of the oscillating support is about to begin.

The worms 22—23 impart movement to the oscillating support at a rate which is constant during the whole of each oscillation, and I prefer that the worms 22—23 130

shall rotate at equal speeds, so that not only will the speed of each traverse be constant, but the speed of traverse in opposite directions shall be constant.

5 As will appear hereafter, it is desirable that the operator, when he stops the machine for inspection or removal of the work, do so when the work is not in contact with the grinding wheel. The tappets 31-32 should be so located on the oscillating support 19 that the tool and work will not be in contact at the period of the reverse. To provide for stoppage of the machine at this time, I provide means for holding both driving elements out of driving relation. I prefer to perform this by a spring pressed pin 48, which may swing with the swinging cage 24 and which is adapted to enter a recess 49 in the stationary frame of the machine when the swinging cage 24 is in mid position, where neither the worm 22 nor the worm 24 is engaged with the worm gear 21. The spring 48 may be provided with any suitable withholding device typified by the handle 50, the cross pin 51, which in the position shown in Fig. 2, holds the pin 48 in retracted position, but which, when the handle 50 is turned 90° can enter the slot 52 when the pin 48 and the recess 49 are in register.

In setting up the machine, it is desirable to provide manual reversing means and to this end I may and preferably do provide, as shown, a handle 33 in the projection 33 (Fig. 1), by which the latter may be shifted at any time in the same manner that it is shifted by the tappets 31-32 at the end of each oscillation. Either the amplitude of oscillation or the field of oscillation, or both, may be changed by changing the location of the tappets 31-32 on the oscillating element.

The grinding tool and the work must at all times during the grinding operation have a predetermined relation to one another. Where the oscillating support carries the work, as shown, the axis of the desired race groove should be aligned with the axis of the oscillating support. A plane passed through the transverse center of the grinding tool should also pass through the center, while the depth of the race groove is determined by transverse feed of the grinding tool. A more even groove is attained when automatic means is provided for this transverse feed, which automatic means preferably feeds the tool transversely, when the tool and work are separated at the point of reverse of oscillation. It is also desirable that the transverse feed of the tool be automatically stopped when the relative oscillation of the work and tool is stopped for any reason or when the two are separated for inspection or gaging of the work.

65 In the preferred construction illustrated,

the work being the oscillated element, I have mounted my grinding tool 18 on a sliding bed 53, which is slideable longitudinally of the machine in ways in the frame 36 in the well known manner by a hand lever 54. Suitable stops are preferably provided for determining the forward or working position of the sliding bed 53 and for preventing undesired retraction thereof from working position, all as is well known in the art.

Mounted transversely of the sliding bed 53 is a feed slide 54, which carries the grinding wheel. This feed slide 54 (Fig. 4) can be fed either manually or automatically by a feed screw 55, engaging a traveling nut 56 formed in the feed slide 54. The feed screw 55 may be rotated manually by a hand wheel 57 through gears 58-59, or automatically in either direction, by means of ratchets 60-61, the actuation of which will now be more fully described.

To actuate the ratchet mechanism, I provide tappets 62-63 on the oscillating support, which are preferably adjustably attached to the oscillating support 19 and which may, as shown, engage annular projection 64 thereon.

The ratchet mechanisms 60-61 and cooperating parts are preferably mounted on 95 and reciprocable with the longitudinal slide 53. By also mounting on the slide 53, the mechanism for transmitting movement from the tappets 62-63 to the ratchet mechanisms 60-61, I insure the discontinuance of 100 the automatic cross feed movement, when the slide 53 is retracted, whether or not the oscillating element carrying the tappets 62-63 is moved either automatically or by the operator.

To this end I preferably supply, as best shown in Figs. 6 and 7, a transverse reciprocating shaft 69, which is preferably reciprocated by a spring 70 in one direction and by tappets 62-63 in the opposite direction. 110 In the preferred construction a projecting pin 71 projects in the path of the tappet 63, while a lever 72, fulcrumed at 73, projects in the path of the second tappet 62, the effective movement of the reciprocating 115 shaft 69 being in the same direction when struck by each tappet, because the motion of the tappet 62 is reversed by the lever 72.

The motion of the reciprocating shaft 69 may be transmitted to the pawl 73 by any 120 suitable means, but I prefer to provide the bell crank fulcrumed at 75 on the longitudinal sliding support 53 and connected through the connecting rod 76 by universal connections to the arm 77 of the ratchet 125 support 78, which is preferably fulcrumed, as shown on the axis of the ratchets 60-61.

The ratchets 60-61 have oppositely disposed teeth and the pawl 73 can be retracted by the knurled handle 79 and reversed 130

thereby alternatively, at the will of the operator, engaging either ratchet 60-61 to feed the transverse feed slide 54 in either direction.

5 The discontinuance of the transverse feed is insured when the oscillation of the oscillating element is stopped because the tappets 62-63 are necessarily stopped, while the discontinuance of transverse feed is insured when the longitudinal slide 53 is retracted, even if the oscillating element continues to oscillate because the shaft 69 with the tappet intercepting elements 71 and 72 are withdrawn from the field of oscillation 10 of the tappets 62 and 63.

15 By the adjustability of the position of the tappets 62-63, I am enabled to effect the transverse feed during the periods when the tool is not in contact with the work and I 20 am enabled to maintain this relation when the amplitude of oscillation, or the field of oscillation of the oscillating element is changed.

25 The setting up and operation of the machine described may be as follows: The work 18 is first firmly clamped in the chuck 9. The slides 14 and 16 are then adjusted to bring the work in such relation to the axis of oscillation of shaft 20 that the axis 30 of the desired arcuate groove of the race coincides with the axis of oscillation. The grinding wheel 18 is then put in place and the forward stop of the longitudinal slide 35 53 is adjusted, so that a plane passed through the center of the grinding wheel, transverse to its axis, will pass through the axis of oscillation. The transverse feed slide 54 may then be adjusted by hand, so that one edge of the grinding wheel 18 is 40 substantially against the work. In practice a roughly finished groove in the work is usually provided prior to the grinding operation. The pin 48 is then preferably entered in the recess 49 and the oscillating element 45 may be swung to one position, in which the grinding wheel, if operating, would no longer be in contact with the race. One of the reverse tappets 31-32 is then set in such 50 position as to slightly displace the pin 33. While the oscillating element is in this position, one of the feed tappets 62-63 may be set to slightly displace its coöperating element.

55 The oscillating element may then be swung to such a position that the work and tool clear each other on the opposite stroke. The remaining reverse tappet and the remaining feed tappet may then be set.

60 The machine is now ready for operation. Of course, this setting operation is only necessary when the race to be ground are dissimilar for the race previously ground. The work may now be rotated about its own axis by imparting power to the pulley 13 65 and the tool may be rotated by imparting

power to the pulley 80. Power may be imparted to the oscillating means by the pulley 26. If now the pin 48 be retracted to permit swinging of the worm cage 24, either worm may be engaged, imparting rotary 70 movement in one direction to the work gear 21 and hence oscillating the oscillatory element. Assuming the initial oscillation to be in the direction of the arrow shown in Fig. 3, the reverse tappet 32 will strike the reverse pin 33, thereby shifting the cam 37 to the left (Fig. 3) and depressing the projection 28 on the lever 40. This will first cause the end 44 of the lever 40 to bear against and compress the spring-supported element 80 46 and will then disengage the catch 43, thereby permitting the spring-supported element 46 to shift the swinging worm cage 24, so that the worm 23 will be disengaged and the worm 22 engaged to reverse the oscillatory movement of the oscillatory element. 85

90 As before stated, I prefer that the transverse feed take place at the period of reversal of oscillation. Therefore, at substantially the same time that the reverse tappet 95 32 engages the pin 33, the feed tappet 62 rocks the lever 72 (Fig. 7), thereby moving the reciprocator member 69 to the left and moving the ratchet 60 or the ratchet 61 as 100 desired, through the medium of the bell crank 74, the connecting rod 76, the arm 77 (Figs. 4 and 5) and the ratchet support 78. This movement of the feed ratchet turns the feed screw 55 through the gears 58 and 59, as heretofore described, thereby imparting feeding movement to the transverse feed slide 54 and to the grinding wheel.

105 The oscillatory support is now on its movement to bring the reverse tappet 31 (Fig. 3) in contact with the reverse pin 33 and the feed tappet 63 (Fig. 6) in contact with the pin 71. When the end of the desired oscillatory movement is reached, these 110 and the coöperating parts will function in substantially the same manner as the corresponding parts heretofore described.

115 As before stated, the machine is preferably stopped at the end of an oscillation. When the operator desires to stop the machine, he turns the handle 50 one-quarter revolution, so that the cross pin 51 registers with the slot 52. The pin 48 will then be 120 spring pressed against the frame 36 and, when the cage 24 is in semi-shifted position, with neither the worm 22 nor the worm 20 125 engaging the worm gear 23, the pin 48 will register with and enter the recess 49, thereby holding both worms out of engagement and stopping the oscillating element. The grinding tool will in this position be disengaged from the work and not as in other positions held against retraction by the arcuate lip of the race. Hence, the longitudinal slide 53 can be retracted by the lever 54 to 130

give an opportunity to inspect or gage the work. Such retraction necessarily renders the feed mechanism temporarily inoperative so that, if necessary, grinding may be resumed exactly where stopped by return of the slide 53 and withdrawal of the stopping pin 48.

The usual ratchet guard or other automatic feed stop mechanism may be applied 10 to the ratchets 60—61 to determine the depth of feed, but the initial operation of a kind should be carefully gaged at intervals to insure the proper setting of the automatic feed stop mechanism.

15 The rate of feed may be controlled by the setting of the feed tappets 62—63, or by any of the usual mechanisms, such as adjustable lost motion or a supplemental guard to render a portion of the stroke of the ratchet 20 inoperative.

25 My invention provides preferably in combination with each other, many advantages which improve the quality of the work over race grinders as previously constructed; and increase the efficiency of the machine.

The oscillatory movement between work and grinding tool is of constant speed throughout each oscillatory movement, thereby insuring a perfect arc without flattening; 30 which has heretofore been occasioned by the spring of the tool, causing more abrasion to those parts of the race where the described relative traverse of work and tool is slowed down.

35 Moreover, not only is the rate of relative traverse constant during each entire traverse at any one setting of the machine, but changes in amplitude of oscillation, or in the field of oscillation, do not effect the speed 40 of relative traverse of work and tool.

Convenient means for insuring the stoppage of the oscillator with work and tool out of contact, not only prevents irregular grinding, but saves much time for the operator, 45 who is thereby enabled to tend more machines than would otherwise be the case, for the oscillation always stops in proper position for relative longitudinal separation of the work and tool for inspection and gaging 50 of the work. The discontinuance of the transverse feed during such inspection and when the oscillatory element is stationary, is insured.

Moreover, a tool of superior stability, 55 durability, certainty of operation and reasonable cost of manufacture is provided, which is adaptable without reorganization of parts to a variety of arcuate race grinding operations, all of which it performs in a superior 60 manner.

While I have shown in the drawings and described a preferred construction of one embodiment of my invention, I wish it understood that my invention is not limited to 65 the embodiment described, but that major

changes involving omission, substitution, alteration and re-arrangement of parts and functions may be made without departing from the scope of my invention, which is best defined in the following claims.

70

Claims:

1. An oscillating grinder comprising, in combination, a rotatable work spindle, a rotatable grinding wheel spindle; an arcuately oscillatory support for one of said spindles, 75 and constant speed oscillating means for automatically imparting oscillatory movement to said oscillatory support, whereby the work and grinding wheel are arcuately relatively traversed at constant speed throughout the contact of said work and grinding wheel.

2. An oscillating grinder comprising, in combination, a rotatable work spindle, a rotatable grinding wheel spindle, an oscillatory support for one of said spindles, 85 mechanical means for imparting oscillatory movement to said oscillatory support, including means for changing the amplitude of oscillation of said oscillatory support, the relative speed of arcuate traverse of the work and grinding wheel being unaffected by change of the amplitude of oscillation.

3. An oscillating grinder comprising, in combination, a rotatable work spindle, a rotatable grinding wheel spindle, an oscillatory support for one of said spindles, mechanical means for imparting oscillatory movement to said oscillatory support and common means for adjusting both the field 100 of oscillation and the amplitude of oscillation of said oscillatory support.

4. An oscillating grinder comprising, in combination, a rotatable work spindle, a rotatable grinding wheel spindle, an oscillatory support for one of said spindles, and oppositely effective driving elements alternately effective, engaging said oscillatory support to rock it alternately in opposite directions.

5. An oscillating grinder comprising, in combination, a rotatable work spindle, a rotatable grinding wheel spindle, an oscillatory support for one of said spindles, a driving element effective to impart oscillatory movement to said oscillatory support in opposite directions, two oppositely effective driving connections coupled for alternate engagement with said driving element, and means on the oscillating support for actuating said alternate engagement of said oppositely effective driving connections.

6. An oscillating grinder comprising, in combination, a rotatable work spindle, a rotatable grinding wheel spindle, an oscillatory support for one of said spindles, driving means for actuating oscillation of said oscillatory support and automatic reversing means for said actuating means, said reversing means including resilient means loaded 125 130

110

115

120

125

by oscillatory movement of said oscillatory support and, when loaded, permitting movement of said oscillatory support without unloading of said resilient means.

- 5 7. An oscillating grinder comprising, in combination, a rotatable work spindle, a rotatable grinding wheel spindle, an oscillatory support for one of said spindles, a driving element effective to impart oscillatory movement to said oscillatory support in opposite directions, two oppositely effective driving connections coupled for alternate engagement with said driving element, and tappet means on the oscillating support for actuating said alternate engagement of said oppositely effective driving connections, said tappet means being adjustable to vary the field of oscillation of said oscillatory element. 10

10 8. An oscillating grinder comprising, in combination, a rotatable work spindle, a rotatable grinding wheel spindle, a support for one of said spindles oscillating about a fixed axis, and means comprising oppositely and alternately effective driving connections for automatically imparting oscillatory movement to said oscillatory support, whereby the work and grinding wheel are alternately relatively traversed at constant speed throughout the contact of said work and grinding wheel. 15

15 9. An oscillating grinder comprising, in combination, a rotatable work spindle, a rotatable grinding wheel spindle, an oscillatory support for one of said spindles; driving means for said oscillatory support including two oppositely effective driving connections, and automatic reverse means for actuating alternate engagement of said driving connections including resilient means, and a shiftable cam shifted by said oscillatory support but independent thereof, for loading said spring means, said cam means and cooperating parts permitting said resilient means to be loaded by said support 20 while preventing movement of said oscillatory support by said resilient means. 25

20 10. An oscillating grinder comprising, in combination, a rotatable work spindle, a rotatable grinding wheel spindle, an oscillatory support for one of said spindles; driving means for said oscillatory support including a worm gear, two worms supported with their axes in fixed relation to each other, but both movable for alternate engagement and disengagement with said worm gear to impart rotary movement in opposite directions to said worm gear. 30

30 11. An oscillating grinder comprising, in combination, a rotatable work spindle, a rotatable grinding wheel spindle, an oscillatory support for one of said spindles, driving means for said oscillatory support including a worm gear, two worms supported with their axes in fixed relation to each other, but both movable for alternate en- 35

35 12. An oscillating grinder comprising, in combination, a rotatable work spindle, a rotatable grinding wheel spindle, an oscillatory support for one of said spindles, means for imparting a sufficient amplitude of oscillation to said oscillatory support to insure reversal when the work and grinding tool are out of contact at the end of an oscillatory stroke, and means under the control of the operator, insuring stoppage of oscillation of said oscillatory support when the work and grinding tool are out of contact at the end of an oscillatory stroke. 40

40 13. An oscillating grinder comprising, in combination, a rotatable work spindle, a rotatable grinding wheel spindle, an oscillatory support for one of said spindles, driving means for said oscillatory support, including a driving element effective to impart oscillatory movement to said oscillatory support in opposite directions, two oppositely effective driving connections for alternate engagement with said driving element and stoppage means for holding both of said driving connections out of engagement with said driving element. 45

45 14. An oscillating grinder comprising, in combination, a rotatable work spindle, a rotatable grinding wheel spindle, an oscillatory support for one of said spindles, driving means for said oscillatory support, including a driving element effective to impart oscillatory movement to said oscillatory support in opposite directions, two oppositely effective driving connections for alternate engagement with said driving element, automatic reverse means for actuating such alternate engagement, and means controllable by the operator for actuating such alternate engagement independently of said automatic reverse means. 50

50 15. An oscillating grinder comprising, in combination, a rotatable work spindle, a rotatable grinding wheel spindle, an oscillating support for one of said spindles, a transversely movable feed support for the other of said spindles, and means on the oscillatory support for automatically actuating reversal of said oscillatory support and for actuating feeding movement of said transversely movable feed support. 55

55 16. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 60

60 17. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 65

65 18. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 70

70 19. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 75

75 20. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 80

80 21. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 85

85 22. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 90

90 23. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 95

95 24. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 100

100 25. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 105

105 26. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 110

110 27. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 115

115 28. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 120

120 29. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 125

125 30. An oscillating grinder comprising, in combination, a rotatable work spindle, a rotatable grinding wheel spindle, an oscillating support for one of said spindles, a transversely movable feed support for the other of said spindles, a longitudinal sliding support on which said feed support is mounted for longitudinal separation of the work and tool, and transverse feed actuating 130

means operatively connected to said longitudinally slidable support and automatically discontinued by withdrawal of said longitudinal sliding support.

5 17. An oscillating grinder comprising, in combination, a rotatable work carrying spindle, a rotatable grinding wheel spindle, an oscillatory support 19, the pivotal shaft 20 for said oscillatory support, the gearing 10 21 on said pivotal shaft, the shiftable cage 24 having gearing 22 and gearing 23 for alternate engagement with the gear 21 as the cage 24 is shifted, and cage shifting means actuated by oscillating of oscillatory sup-

15 port 19.

18. An oscillating grinder comprising, in combination, a rotatable grinding wheel spindle, an oscillatory work carrying support 19, constant speed driving means for 20 rocking said oscillatory work carrying support relative to said grinding wheel spindle, and reversing means for said driving means, including resilient means for storing energy and escapement means providing for sudden 25 release of such stored energy.

19. An oscillating grinder comprising, in combination, a rotatable grinding wheel spindle, an oscillatory work carrying support 19, constant speed driving means for 30 rocking said oscillatory work carrying sup-

port relative to said grinding wheel spindle, and reversing means for said driving means, including the tappets 31-32 carried by said work carrying support the cam 37, the rocking pawls 40-41 alternately engaged by 35 said cam, the shifting frame 24, and the spring supported elements 46-47 co-operating with the catchers 43-44 for actuating the shifting of the frame 24 to reverse the direction of oscillation of the oscillating 40 work carrying support 19.

20. An oscillating grinder comprising, in combination, a rotatable grinding wheel spindle, a rotatable work carrying spindle, an oscillatory support 19 for one of said 45 spindles, a transversely movable feed support 54 for the other spindle, a longitudinally movable support 53 for said feed support, tappet means on the oscillating support, the transverse feed screw 55 and reciprocating means carried by said longitudinally movable support 53 for transmitting power from said tappet means to said transverse feed screw 56, said tappet means and said reciprocating means being operatively 55 disconnected on retraction of said longitudinally movable support.

In testimony whereof, I have signed my name to this specification.

FREDERICK HENRY HALSTEAD.
